UNITED STATES PATENT OFFICE

GEORGE L. BLAKESLEY, OF MERCED, CALIFORNIA

NONGLARE ATTACHMENT FOR HATS

Application filed April 15, 1929. Serial No. 355,189.

This invention relates to automobile driving aids and particularly to a non-glare attachment or glare shield to protect the eyes of the driver from the glare of approaching lights or from the rays of the sun when low in the heavens.

The principal object of my invention is to provide a device of this general character which instead of being mounted on the motor vehicle itself, as is now the case, is arranged to be detachably and adjustably supported by the brim of the hat or the visor of the cap of the driver. The device is so arranged that it is not ordinarily in the way so as to impair full and natural vision but when the occasion arises the driver by a very slight forward tipping of his head or hat causes the device to be lowered sufficiently to shield his eyes and cut the glare effectively, while still enabling him to properly see the road ahead. The device is also constructed so as to be very light so that it will not exert sufficient downward pull on the brim to affect the natural hang of the same or be noticed by the wearer. This non-glare shield device therefore requires no manual manipulation to enable it to be adjusted to all ordinary light conditions, since, as above stated, a slight head movement places it in or out of the path of any glaring rays.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective view of my improved attachment as applied to the brim of a hat.

Fig. 2 is a similar view of the device detached.

Fig. 3 is a cross section of the device.

Referring now more particularly to the characters of reference on the drawings the shield portion of the attachment comprises a

sheet 1 of translucent material, such as celluloid, which is colored green or any other desired soft and glare-cutting color and of substantially rectangular and relatively wide shape. This sheet is preferably arranged in connection with another sheet 2 behind the same and of the same length but of lesser height. These two sheets are held in unitary association with each other and with a stiffening strip 3 therebetween by a channel-shaped binding element 4 of fabric or other material sewed or otherwise suitably connected to the upper edges of the sheets and strip, which upper edges all lie in common alinement.

These pieces are all initially separate and are of a non-stretchable nature. Before tacking or sewing the same together they are given an initial longitudinal curvature so that when they are then connected this curvature is retained without the need of any relatively heavy metal parts, or end ties, being necessary to cause the finished shield to hold its curved shape.

In order to detachably mount the shield in connection with the brim of a hat I provide a clip which is rigidly attached to the shield and adapted to detachably engage the brim of a hat. This clip may be of more or less standard form having opposed flat jaw plates 5 between which the brim 6 is adapted to pass, a spring 7 holding the jaws yieldably closed, and finger grip elements 8 provided with the jaws outwardly of the spring. Formed with the lower jaw and depending therefrom is a channel-shaped portion 9 adapted to be slipped over and to be pinched into frictional engagement with the top of the shield centrally between its ends. The jaws are preferably of relatively large area so as to engage a considerable portion of the hat brim, and are cut out as shown to lighten the same as much as possible.

The member 9 is disposed between the spring and the outer ends of the jaws so that when the brim is inserted as far as possible between said jaws the shield itself will be under the hat, the curvature of the shield from end to end being substantially that of the forward portion of the brim. The upper

edge of the shield is then disposed close against the brim and follows around the same so as not only to tend to prevent any sagging of the brim but keeps out light from between the brim and the top of the shield.

5 Also said member 9 is disposed at a forward and downward angle relative to the horizontal plane of the jaws so that the shield sets at a corresponding angle and light rays striking the shield from ahead are deflected somewhat upwardly.

10

The double thickness of the shield toward the top, had by reason of the two superimposed colored sheets, effectively cuts the glare of very strong lights such as that of the sun; while the single thickness of the shield below is sufficient to cut the glare of most headlights while still enabling the driver to see the road therethrough. Also the height of the shield is not great enough to prevent the driver from actually looking under the shield to obtain an unobstructed view of the roadway and other features immediately in front of his car. The shield being detachably mounted on the hat it may be placed or removed instantly and may also be adjusted laterally of the brim without disturbing the setting of the hat on the head, as the position of the lights relative to the driver may demand, and so as to give the best results with the least head movement.

While I have here shown and preferably use a shield element and clip made in the shape and relatives sizes as shown, it will be obvious that various departures may be made from such showing without departing in the slightest from the spirit of the invention, which in the main is to provide a non-glare shield for detachable and depending association with a head cover.

40 Having thus described my invention what I claim as new and useful and desire to secure by Letters Patent is:

1. In connection with a non-glare eye shade, a clip comprising spaced jaws to receive the brim of a hat therebetween, and a channel shaped member cut from and depending from the lower jaw intermediate its ends to frictionally engage the upper edge of the shade.

45 2. In connection with a non-glare eye shade, a clip comprising spaced jaws to receive the brim of a hat therebetween, and a channel shaped member cut from and depending from the lower jaw intermediate its ends with an outward slant toward its lower end to snugly receive the upper edge of the shade, whereby the latter will be disposed with a corresponding slant.

60 In testimony whereof I affix my signature.
GEORGE L. BLAKESLEY.
